3 Claims. (Cl. 315—30)

This invention relates to electron devices and more specifically to those of the cathode ray tube type in which use is made of an intensity modulated electron beam. In these devices, an electron gun is normally provided to generate and form an electron beam of small cross-sectional area.

One particular application of the cathode ray tube is within the television industry, in which, the electron gun is utilized within the cathode ray tube to generate an electron beam of small cross-sectional area. This beam is scanned across an electron sensitive screen which emits light in response to the electron bombardment and thereby displays a light image corresponding to the intensity modulation on the electron beam. Various types of electron guns have been employed in the picture tube industry and one particular structure which is representative of the common type gun structure is in United States Patent No. 2,773,212, entitled "Electron Gun" by J. H. Hall, issued December 4, 1956, and assigned to the same assignee.

The conventional electron gun utilized in television display tubes is constituted basically of two axially arranged systems. These two systems are the beam forming and modulation system and the principal lens system. The purpose of the beam forming and modulation system is to provide a well defined electron beam of controlled intensity to the principal or main lens. The principal lens provides the necessary focusing of the electron beam emitted from the beam forming and modulating system to a small spot on the viewing screen. The principal lens of the electron gun is usually of the electrostatic or electromagnetic type. Most electron guns including the ones presently used in the television industry possess a beam forming and modulating system which comprehends a lens known as an immersion lens. This invention is directed primarily to the beam forming and modulating system of the electron gun and the description and drawings will refer principally to this portion of the gun.

In the present type of television display systems, the electron beam in the cathode ray tube must be amplitude modulated within wide limits in order to reproduce the desired picture high lights, low lights, and all intermediate values of brightness for adequate picture presentation. For example, in a direct viewing tube the electron beam may reach peak values of currents as high as 1500 microamperes in the high light portion of the picture and must go as low as zero microamperes for beam cutoff in the black regions. To modulate the electron beam throughout this large current range, it is required that a relatively large picture or video signal be applied to the gun to modulate the intensity of the electron beam. A typical amplitude of video voltage required to drive the electron beam from zero up to 1500 microamperes is about 60 volts in the modern television tube. This large amount of drive that is required is primarily due to the low transconductance of the present electron gun structure.

In conventional television receivers, the video detector supplies a signal which is normally less than 5 volts peak-to-peak. Due to this low value, the signal cannot be utilized to directly drive the present cathode ray tubes. It is necessary that the video signal from the detector be amplified to a much higher level of the order of 25 times.

2

This requires that the video amplifier be capable of providing a relatively large gain throughout the entire 3.5 megacycles per second bandwidth of the conventional picture signal. It is, therefore, necessary that the video amplifier be a relatively high power and expensive device because of the high output drive voltage and the large total shunt capacitance associated with the picture tube drive circuit. This capacitance is primarily made up of the output capacitance of the video amplifier tube, the input capacitance of the cathode ray tube and the additional capacitance due to wiring sockets and other components associated with the picture tube drive circuit.

The primary limitation in reducing the video drive of the present cathode ray tube is that due to the extremely stringent electron optical requirements which must be met by the electron gun in order to produce sharp and bright pictures. Due to the limitation of presently available electron optical lenses, only an extremely small area of the electron emissive coating of the cathode can be utilized for the formation of the electron beam. The high resolution requirement and the high brightness are mutually conflicting in that the size of the spot increases with increasing beam current. The industry has attempted in many ways to solve this problem, but at this time little success has been had in reducing the drive requirements of the cathode ray tube.

The applicant in his copending application entitled "An Electron Device," Serial No. 705,583, filed December 27, 1957, and assigned to the same assignee, discloses a device in which an electron optical section of the electron gun is designed to meet the resolution and brightness requirements and a transconductance section is designed to meet the drive requirements. The two sections are entirely separated in function. The structure described in the copending application is of the screen grid type of electron gun.

This invention is directed to a modification of the copending application which provides a structure which may be utilized either with a screen grid type of electron gun or any other type of electron gun regardless of whether a screen grid is utilized. In the structure described herein, the final anode of the transconductance section which basically provides a video amplifier section operates at a potential entirely distinct from the potential applied to the first accelerator anode of the electron gun itself. This is accomplished in this invention because the control grid of the electron gun is utilized to perform the multiple function of the intensity control of the electron beam and also the anode of the amplifier or transconductance section of the electron gun. The structure described herein may be operated with a positive going or black positive signal applied to the control grid of the amplifying section of the cathode ray tube. A black positive signal is one which causes negative variations of the electron beam current by means of positive variations of the video signal. Thus black or cut off is achieved when the video component of the signal reaches its peak positive value.

It is accordingly an object of this invention to provide a high transconductance wideband cathode ray gun.

It is another object to provide an improved high transconductance wideband electron gun structure which offers maximum flexibility of design to achieve the highest performance capabilities in relation to the operational requirements imposed on the electron gun.

It is another object to provide an improved high transconductance wideband television gun structure which provides a favorable transfer characteristic for better tonal rendition of the reproduced images.

It is another object of this invention to provide a high transconductance wideband electron gun in which the

direct current component contained in the input signal is preserved in the modulated cathode ray beam.

It is another object to provide an electron beam modulation system which provides amplification of the video signal applied which may be adapted to be utilized in any electron gun structure.

These and other objects are effected by my invention as will be apparent from the following description taken in accordance with the accompanying drawing, throughout which like reference characters indicate like parts and in which:

FIGURE 1 is a view of a cathode ray tube partly in section embodying the principles of my invention;

FIG. 2 is an enlarged sectional view of a portion of the electron gun structure illustrated in FIG. 1;

FIG. 3 is an operational view of a portion of the electron gun structure shown in FIG. 1 to explain the operation of the invention;

FIG. 4 illustrates a modification of the operational view illustrated in FIG. 3;

FIG. 5 illustrates another operational view which is a modification of the electron gun structure shown in FIG. 1;

FIG. 6 is a top sectional view of a modification of the structure shown in FIG. 2; and

FIG. 7 is a side view, partly in section, of the view shown in FIG. 6.

Referring in detail to FIG. 1, there is shown a cathode ray tube embodying my invention. The tube is comprised of an envelope 12 having a tubular neck portion 14, a flared bulb portion 16 and a face plate portion 18. The face plate or viewing portion 18 of the envelope 12 has a suitable fluorescent coating 20 of a phosphor material deposited on the inner surface of the face plate 18 and may have an electron permeable electrically conductive coating 22 deposited on the exposed surface of the phosphor coating 20 as illustrated in FIG. 1. The flared portion 16 of the envelope 12 is provided with an electrically conductive coating 24 of a suitable material such as carbon or aluminum which extends into the neck portion 14 of the envelope 12.

An electron gun 30 is mounted within the neck portion 14 of the envelope 12. The gun 30 consists essentially of a beam forming and modulating system and a principal focusing electron lens electrode system. The conducting coating 24 on the interior surface of the flared bulb portion 16 serves as an anode of the cathode ray tube and is provided with a suitable voltage supplied by means of an exterior terminal 25. The electron gun described and shown in FIG. 1 is of the electrostatic focus type. There is a suitable deflection system provided for deflecting the electron beam to scan a raster on the screen 20. In the specific embodiment shown, the deflection system is illustrated as an electromagnetic deflection yoke 28.

The modulating system of the electron gun 30 in FIG. 1 is illustrated in more detail in FIG. 2, and in the operational view shown in FIG. 3. The modulating system illustrated in FIG. 2 consists of a modulating grid 40 which is formed in the shape of a cup member with the open portion facing to the rear with respect to the screen 20 of the cathode ray tube. A spacer member 42 of a suitable insulating material such as mica or ceramic is mounted to the edge of the cup-shaped member 40 by suitable means. A centrally located aperture 44 is provided in the bottom portion of the cup-shaped member 40. The cup-shaped modulating grid 40 is of an electrically conducting material. The spacer 42 is provided with apertures through which extensions 41 provided on the edge of the cup-shaped member 40 are inserted. The extensions 41 may be deformed in a well-known manner in order to lock the spacer 42 securely to the modulating grid 40.

An indirectly heated cathode 46 is provided for supplying the necessary electron emission for the electron beam of the gun structure and is positioned within the cup-

shaped modulator grid 44. In the specific embodiment shown, the cathode 46 is comprised of a tubular member 48 of electrically conductive material which is coaxially positioned within the modulator grid 40 and of a shorter length than the depth of the cup-shaped grid 40. The end of the tubular member 48 adjacent the bottom of the cup-shaped grid 40 is closed with an electrically conductive member 47 and an electron emissive coating 49 is provided on the exterior surface of this closed end portion 47. The electron emissive coating 49 is provided adjacent to the aperture 44 in the bottom of the cup-shaped grid 44 and is of a greater area than the aperture 44 and closely spaced thereto. The beam forming cathode 46 may be supported within the cup-shaped grid member 40 in any well-known manner and in the specific embodiment shown is retained by support member 50 attached to the outer surface of the tubular member 48 with the other end of the support member 50 anchored within apertures provided within the spacer element 42.

The amplifying section of this modulating structure is positioned on the opposite side of the spacer 42 with respect to the modulator grid 44. The amplifying section is mounted on the spacer 42 and consists of a cathode 52 which is comprised of a tubular member 54 of electrically conducting material of similar diameter as the tubular member 48. The two members 54 and 48 are coaxially positioned and will be located substantially on the axis of the electron gun 30. One end of the tubular member 54 is mounted within an aperture provided in the spacer element 42 and a spacer element 55 of similar material as element 42 is also provided at the opposite end of the tubular member 54. The spacer element 55 is also provided with a centrally located aperture through which the tubular member 54 passes and is positioned thereby. An electron emissive coating 56 of suitable material is provided on the exterior surface of the tubular member 54 between the two spacer elements 42 and 55. A heater element 58 is provided in the tubular member 54 and extends into the tubular member 48 which is a part of the beam forming cathode 46 so as to provide the necessary heat for both cathodes. The heater 58 provides the necessary energy to excite electron emission from the electron emissive coatings 49 and 56. A tubular control grid 60 consisting of a plurality of parallel elements or of a mesh structure of electrically conductive material is positioned so as to surround the cathode 52 of the amplifier section. The control grid 60 is supported at its ends by the two spacer elements 42 and 55. It may be desirable to use more than one grid member. An anode or intercepting electrode 62 is positioned so as to surround both the cathode 52 and the control grid 60 and to intercept the electrons emitting the cathode 52 after passing through the control grid 60. The anode 62 is also tubular in shape and is supported at opposite ends by the spacer elements 42 and 55. The anode 62 is of an electrically conductive material and of suitable strength to securely lock the amplifying section to the spacer element 42 which is also common to the beam forming and modulating section. An electrical connection is made by a suitable conductor 64 between the amplifying anode 62 and the modulator grid 40. The technique of assembling the amplifying section is similar to that utilized in the receiving tube art.

Referring to FIGS. 1 and 3, a screen grid 70 is provided between the modulating grid 40 and the screen 20 of the cathode ray tube. The screen grid 70 is of conventional design and consists of a cup-shaped member having its open end toward the screen 20 and the bottom portion adjacent the modulating grid 40. A centrally located aperture 72 is provided in the bottom portion of the screen grid and is aligned with the aperture 44 in the modulating grid 40.

The principal focusing electrode lens system illustrated here consists of a first anode 76 adjacent the screen grid 70 comprised of a tubular or skirt member and a second

anode 80 also a tubular member spaced along the axis of the tube from the first anode 76. The end of the skirt portion of the first anode 76 nearest the screen 20 is closed by a diaphragm transverse and substantially perpendicular to the axis of the tube. The diaphragm is provided with a centrally located aperture. The end of the second anode 80 which faces the first anode 76 is also provided with a diaphragm having a centrally located aperture therein. In the specific embodiment shown, the facing ends of the first and second anode have a reduced portion. Means in the form of contact members 77 are provided on the end of the second anode 80 nearest the screen 20 for making electrical contact to the coating 24 and also to assist in positioning the electron gun 30 within the tube neck 14. The first and second anodes 76 and 80 are connected together electrically and are supplied with voltage from the coating 24. A sleeve or focusing electrode 84 also tubular with a larger diameter than the first and second anodes 76 and 80 surrounds the space between the first and second anodes 76 and 80 and is coaxial with the anodes. The principal focusing electrode system comprised of the electrodes 76, 80 and 84 is of a conventional univoltage type structure and is only an example of a suitable principal focusing lens system.

The electrodes 40, 70, 76, 80 and 84 of the electron gun structure are normally spaced by providing radially projecting anchor pins 90 from the electrodes with the pins embedded in longitudinal support glass rods 92 as illustrated in FIG. 1.

Referring in detail to FIG. 3 which is an operational showing of the structure shown in FIG. 1, the second anode 76 is normally operated at a potential of about 15,000 volts and a suitable source of potential is illustrated by the battery 100 which has its positive terminal connected to the anode 76 and the negative terminal connected to ground. It should be remembered that the screen 20 which is collector or anode of the electron beam is operating at the same potential as the second anode 76. The screen grid 70 is connected to a terminal 101 on the battery 100 to provide the necessary screen grid voltage which may be, for instance, of about 300 volts positive with respect to ground. The modulator grid 40 is connected through a load resistor 102 and an inductance 104 to a terminal 103 on the battery 100 which provides a positive potential lower than the one applied to screen grid 70 of about 100 volts positive with respect to ground. The beam forming cathode 46 is also connected to a terminal 105 on the battery 100 such that its potential, positive with respect to ground, may be made arbitrarily larger than the potential applied to the modulator grid 40 of the amount required to cut the beam off. This voltage may be about 60 volts.

The cathode 52 of the amplifying section is connected to ground and the control grid 60 of the amplifying section is connected to a video source 108. A suitable biasing source illustrated as a battery 110 may also be provided. The anode 62 is at the same potential as the modulator grid 40. The potential difference between the modulator grid 40 and the amplifier cathode 52 is amplitude modulated in accordance with the input video signal applied to the control grid 60 of the amplifying section. This is accomplished by means of the load impedance 102 which is inserted into the circuit of the modulator grid 40. The electron optical system of the gun has both the beam forming cathode 46, the screen grid 70 and the anode 76 in FIG. 5 at fixed potentials. The beam modulation within the beam forming portion of the gun occurs by natural grid drive.

In FIG. 4, the screen grid 70 and the modulator grid 40 of the beam forming section are coupled together by a resistor 112 to achieve the combined actions of both grids 40 and 70 in modulating the electron beam. The modulator grid 40 in this structure is driving the screen grid 70. It also can be appreciated that the coupling resistor 112 may be replaced by a coupling capacitor.

Brightness control may be obtained by varying the potential of the beam forming cathode 46 from the battery 100. Gain control within the amplifying section may be obtained by varying the value of a resistor 114 connected to the amplifying cathode 52 as is illustrated in FIG. 4. Gain control may also be obtained by varying the bias applied to the control grid 60 of the amplifying section.

With a black positive signal, it can be seen that the sync pulses contained in the composite video signal supplied by the video detector source 108 to the control grid 62 represent the maximum positive value of said composite video signal and therefore that the current in the amplifying section is at its peak value during the sync pulses. The voltage of the modulator grid 40 will be at its minimum value during the sync pulses. The potential difference between modulator grid 40 and the beam cathode 46 will be at its maximum negative value so that the beam current is at a minimum value or cutoff. During the video portion of the input signal from the video detector source 108, the signal will be less positive and the current within the amplifying section will decrease. The voltage difference between the beam forming cathode 46 and the modulator grid 40 will become less negative with the result that the beam current in the electron gun will start flowing and increase from zero to a value determined by the input signal.

The peak level of said beam current will be obtained in correspondence of the minimum level of the input signal. By taking advantage of the curvature of the transfer characteristic of the amplifier section, it is possible to vary within broad limits the gamma of the electron gun.

In FIGS. 6 and 7, a modified structure is illustrated. In this structure, the cathodes are positioned transverse to the electron beam. The modulator grid 120 comprises a tubular structure having an aperture 122 centrally located in one side thereof. The tubular modulator grid 120 is supported between two spacer members 126 and 128 positioned at opposite ends of the tubular grid 120. Positioned within the tubular modulator grid 120 are the cathode members 130 and 132. The cathode members consist of two half sections of a tubular member which are insulated from each other. The cathode 130 is provided with an electron emissive coating 131 on one surface near the aperture 122 in the grid 120 and supplies the electron emission for the beam forming structure. The other half section is the amplifier cathode 132 which has an electron emissive coating 133 which provides the electron emission for the amplifying section of the structure. A common heater 136 may be utilized to heat both the beam forming cathode 130 and the amplifying cathode 132. The control grid 138 for the amplifier may be a frame like structure positioned adjacent the amplifying cathode 132 and also supported by the spaced elements 126 and 128. The modulator grid 120 also serves the dual function of also being anode of the amplifying section. In the specific embodiment shown, the re-entrant portion 140 is the active area of the anode or intercepting electrode. The first anode 76 of the principal lens is adjacent the modulator grid 120 and the screen grid 70 in FIG. 1 is omitted. This type of gun lends itself to structures possessing very low shunt capacitance which is a highly desirable feature particularly whenever large bandwidths are involved.

While I have described my invention in only a few forms, it will be obvious to those skilled in the art that it is not so limited but is susceptible of various changes and modifications without departing from the spirit and scope thereof.

I claim as my invention:

1. An electron beam forming and modulating electrode system within an evacuated envelope comprising a first and a second electron discharge path, said first path comprising a first cathode operating at a first potential, a dual

function electrode operating at a more positive potential with respect to said first potential having a first portion for intercepting the electrons emitted from said first cathode, a control grid positioned between said first cathode and said dual function electrode for controlling the electron flow in said first discharge path, said second path comprising a second cathode, an anode, and said dual function electrode having a second portion adjacent to said second cathode and having an aperture therein, said dual function electrode modulating and forming an electron beam from the electrons emitted by said second cathode, said second cathode operating at a positive potential with respect to said first potential.

2. A high transconductance cathode ray tube comprising an envelope and having therein an electron gun structure to provide an electron beam directed to impinge upon a target member, said electron gun structure comprising an amplifier including a cathode, an amplifier control grid and a multipurpose anode electrode, said electron gun also including an electrode assembly having an electron beam source, a control grid adjacent said electron beam source for controlling said electron beam, said multipurpose electrode being formed to provide the anode for said amplifier and said control grid for said electrode assembly, said cathode operating at a potential less than the potential applied to said electron beam source.

3. A high transconductance cathode ray tube comprising an envelope and having therein an electron gun structure to provide an electron beam directed to impinge upon an image display screen within said envelope, said electron gun structure comprising an amplifier including a cathode, an amplifier control grid and a collecting electrode, said electron gun structure also including an electron beam source, a control grid, and an accelerating anode for accelerating and focusing the electrons within said electron beam, said collecting electrode electrically connected to said control grid and operating at the same potential as said control grid by means of a direct current connection, said cathode operating at a potential less than the potential applied to said electron beam source.
